(57) **CLAIM**

The ornamental design for a step trash can, as shown and described.

DESCRIPTION

FIG. 1 is a perspective view of a step trash can showing my new design;

FIG. 2 is a front elevational view thereof;

FIG. 3 is a rear elevational view thereof;

FIG. 4 is a left side perspective view thereof;

FIG. 5 is a right side perspective view thereof;

FIG. 6 is a top plan view thereof;

FIG. 7 is a bottom plan view thereof;

FIG. 8 is another perspective view thereof, with the lid closed;

FIG. 9 is a rear perspective view thereof;

FIG. 10 is another front perspective view thereof;

FIG. 11 is another perspective view with the lid closed;

FIG. 12 is another perspective view with the lid half-open; and,

FIG. 13 is another perspective view with the lid open.

The broken lines shown in the Figures are for the purpose of illustrating environment and form no part of the claimed design.
